INTERCHANGEABLE INSERT SUPPORT FOR SEWING MACHINES

Arnold Zanger, New York, N. Y.

Application January 17, 1955, Serial No. 482,223

1 Claim. (Cl. 311—12)

This invention relates to support devices for sewing machines. More particularly, the invention has reference to a support board in the nature of an insert, removably and fixedly connectable to the top of a sewing machine table or cabinet, to support a selected make or model of sewing machine.

Heretofore, every make or model of sewing machines, differing in some respect from other machines, has required a cabinet or table top specially cut to support the same. Said table top or cabinet has, as a result, been incapable of supporting any other machine except that for which it has been particularly designed.

This is, as will be appreciated, a somewhat undesirable situation. It is clearly a matter of some expense to form differently shaped table tops according to the particular makes and sizes of sewing machine models. Accordingly, it is the main object of the present invention to provide an insert or support board for a sewing machine which will be designed to receive a particular machine, and will further be designed so as to be removably and fixedly mountable upon a table or cabinet top, with said table or cabinet top so designed as to receive any of a substantial number of inserts differing from one another in respect to the type of machine to be supported thereby.

A further object of importance is to so shape the insert as to cause the outer configuration of the same to substantially match an insert-board-receiving opening formed in the table or cabinet top, with that portion of the insert that is shaped to receive the base of the sewing machine to be supported being formed to the special shape and dimensions that render the insert capable of supporting the particular machine.

Still another object is to provide means on the cabinet or table top extending adjacent the insert-receiving opening thereof so shaped as to support the insert in the provided opening, while at the same time permitting the fixed connection of the insert to said means, thereby to prevent relative movement or vibration between the table top and insert.

Still another object is to so design the above mentioned means as not to interfere in any way with the passage of a drive belt from the sewing machine through the table top and insert to a drive motor mountable upon the underside of the table top.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a side elevational view of a sewing machine table having mounted therein the insert formed according to the present invention, the dotted lines showing a sewing machine, its associated drive motor, and related parts.

Fig. 2 is a fragmentary top plan view of the table and insert, on an enlarged scale, portions of the insert being

2

broken away, the sewing machine being shown in dotted lines.

Fig. 3 is a transverse sectional view on line 3—3 of Fig. 2, on the scale of Fig. 1.

Fig. 4 is a transverse sectional view on line 4—4 of Fig. 2, the scale being enlarged above that used in Fig. 2.

Fig. 5 is a perspective view of the insert per se.

Fig. 6 is a view similar to Fig. 2, showing a modified insert mounted in the sewing machine table.

Fig. 7 is a transverse sectional view, on an enlarged scale, substantially on line 7—7 of Fig. 6.

The reference numeral 10 has been applied generally in the several figures of the drawing to a sewing machine table including corner legs 12 secured to and supporting a horizontal, flat, table top 14. Although a table is illustrated, obviously the structure can be of closed, cabinet-like construction if desired.

In any event, a drive motor 16 is mounted against the underside of the table top (Fig. 1) in the usual manner, and by means of a belt 18 passing from the motor to a location above the table top, drives a sewing machine having a housing 20 and head 22.

Ordinarily, the sewing machine is mounted directly in an opening provided in the table top, which opening is shaped to receive a particular machine, and is not adapted to receive any other machine differing from the intended machine in respect to location of its drive belt, the size of its base, and the outer configuration of said base. However, in accordance with the present invention, in the illustrated sewing machine table there is formed a large, rectangular opening 24, opening upon the front edge of the table top as shown to particular advantage in Figs. 2 and 6. The opening 24 is substantially greater than the usual opening formed in a sewing machine table top to receive the machine housing and head.

The insert plate structure member constituting the present invention has been illustrated per se in Fig. 5, and in the form of Figs. 1—5, comprises a rectangular, flat board or plate structure member 26, the thickness of which is equal to the thickness of the table top 14, and the outer configuration of which corresponds to the shape of opening 24. As will be noted in Fig. 2, in length and width the support plate or board 26 is slightly smaller than the corresponding dimensions of the opening 24, by perhaps $\frac{1}{8}$ of an inch. This facilitates the seating of the support board 26 in the opening 24, without difficulty and without projection of the front edge of the support board forwardly beyond the front edge of the table top.

Formed in the support plate or board 26 is a series of openings located at the corners thereof, said openings including a pair of back or inside corner openings 30, and a pair of outside corner or front openings 36.

Extending longitudinally of opening 24, at the open front thereof, is a rigid, relatively narrow, straight front support bar 32. Bar 32 is greater in length than opening 24, the ends of the bar underlying the table top 14, beyond the ends of opening 24, as best shown in Figs. 1 and 2. The support bar 32, at locations spaced inwardly from the ends thereof, has apertures 34 that register with the openings 30 (see Fig. 1) when the plate 26 is fitted into opening 24. The bar 32, at locations beyond the ends of opening 24, has other openings or apertures 36.

Bolts 38 extend through the registering openings 30, 34, to connect the front edge portion of the plate 26 to the bar 32 when the plate 26 is disposed in opening 24 with its front edge portion-supported upon the bar 32. Wing nuts or equivalent means are threaded onto the bolts against the underside of the bar 32 as shown in Fig. 1.

Connecting bolts 40 are extended through the openings 36, and through openings formed in the table top in registration with said openings 36, thereby to fixedly

connect the bar 32 to the table top in the position previously described herein.

At the back corners of the openings 24, there are provided back support bars or brackets 42. These are also formed from strong, relatively narrow, metal bar or strap material, but as shown in Fig. 2, these are substantially shorter in length than the front support bar 32, with each of the rear corner support bars extending diagonally of its associated corner. The opposite ends of each corner support bar 42 underlie the table top 14, and are formed with openings registering with openings formed in the table top to receive connecting bolts 44. The midlength portion of each corner support bar 42, which is exposed in the corner of the opening 24, has an aperture receiving a bolt 46. The bolts 46 extend through the rear corner openings 28 of the plate 26, said openings 28 being in registration with the midlength openings of the rear corner support bars 42.

The corner bars 42 support the rear corners of the plate 26, as will be apparent, and through the medium of the bolts 46, which are fitted with wing nuts, the plate 26 is securely fixed at its rear corners to the table top.

It will be seen that in this way, the plate 26, though readily removable for use of any of a selected number of said plates differing from one another with respect to the type of machine which they can support, is swiftly and easily attachable to or detachable from the table top, and when attached to the table top, will be held securely against vibrations relative to said top.

Means is provided in the plate 26 to facilitate extension of the drive belt to the supported sewing machine, and care is taken that said means does not interfere with movement or proper positioning of the drive belt 18. As shown in Fig. 2 and also in Fig. 4, a short support bracket 48 is spaced longitudinally of the rear edge of the opening 24 from one of the corner support bars 42. Bracket 48, at one end, underlies the table top, and has an opening receiving a connecting bolt 50 which extends through the table top. The other or free end of the bracket 48 projects inwardly of the opening, to underlie the board or plate 26 and aid in providing a support therefor.

The bracket 48 and the adjacent corner support bar 42 are disposed in close proximity to and at opposite sides of a transverse slot 52 formed in the plate 26. Slot 52 extends adjacent one end of the plate 26, from the midwidth area of said plate 26 to the back edge thereof, and is in registration, at said back edge, with a transverse slot 54 formed in the table top 14. The slots 52, 54 cooperate when the plate 26 is properly supported to define an elongated opening through which the drive belt 18 extends. Proper support at this particular location is provided by the bracket 48 and the corner support bar 42 adjacent thereto.

Assuming that it is desired to mount a particular sewing machine such as that shown in Figs. 1-4 upon the sewing machine table, the support plate 26 shaped to receive said sewing machine is used. The support plate 26, at the corners of a rectangular opening 56 formed therein, has corner support ledges 58, each of which is covered with a suitable cushioning pad of rubber, felt, or the like. The sewing machine housing 20 includes the usual flat base 60, and said base is of a shape and dimensions corresponding to those of the opening 56. Base 60 is thus seated snugly in opening 56, with the corner portions of the base effectively supported upon the cushioned ledges 58.

When the sewing machine is so supported, the drive belt 18 can be extended through the registering slots 52, 54, and the structure is ready for use.

In Figs. 6 and 7, there is illustrated a different insert plate structure member 26^a constructed to support a different type of sewing machine designated at 20^a. This illustration is for the purpose of showing how different inserts, supporting various types or sizes of machines,

can all be interchangeable in respect to a single sewing machine table top such as that shown at 14 having the rectangular opening 24.

In the modified form, the insert plate 26^a has an outer configuration matching that of the insert 26. As a result, the insert plate 26^a can be supported upon the front support bar 32 and the rear corner support bars 42 as well as on bracket 48. In the modified form, however, the opening 56^a is substantially different in respect to its dimensions and shape from opening 56, since a different type of sewing machine 20^a, having a base 60^a corresponding to opening 56^a is to be supported. Opening 56^a, in this instance, is not provided with corner support ledges 58, but rather, has longitudinally extending front and rear ledges 58^a (Fig. 7), merging into end ledges 59^a, adapted to support the ends of the sewing machine.

The ledges 58^a, 59^a are quite narrow as compared to the area of the corner support ledges 58, and this is for the purpose of providing clearance for a semicylindrical, depending portion 62 of the sewing machine housing 20^a. The portion 62 has ears 64, capable of being bolted to the inner, vertical surfaces of the front and rear ledges 58^a.

25 The belt-receiving slot of the insert plate 26^a has been designated at 52^a, and as in the first form of the invention, is aligned with the slot 54 of the table top 14.

Further, in the modified form, the corner openings 30^a are used, and as in the first form, register with the openings 34 of the bar 32, to receive the connecting bolts 38.

35 The rear corner openings of the modified adapter 26^a will be disposed similarly to the rear corner openings 28 of the first form of the invention, to permit extension of the bolts 46 therethrough.

40 It will be seen from the above that a single table top 14 can be manufactured, adapted to receive all the different sewing machines of the particular manufacturer. Further, it will be noted that the table top 14 can even be adapted to receive the sewing machines of any manufacturer, simply by manufacture of the table top 14 with a plurality of inserts being also manufactured each of which is adapted to support a different make, model, or size of sewing machines. The structure is particularly useful in businesses in which, for example, there is a large operation in respect to the conversion or renewing of sewing machines, and the sale of traded-in equipment. In such an establishment, merely by manufacture of a single type of table and a plurality of inserts for receiving different machines, any machine can be mounted attractively upon a table, and when so mounted, will appear to have been designed particularly for installation on said table or cabinet.

45 While I have illustrated and described the preferred embodiments of my invention, it is to be understood that I do not limit myself to the precise constructions herein disclosed and the right is reserved to all changes and modifications coming within the scope of the invention as defined in the appended claim.

50 Having thus described my invention, what I claim as new, and desire to secure by United States Letters Patent is:

55 In the combination of a power-table having a table top provided with a rectangular cutout therein opening outwardly of one side of the table top and with openings adjacent the front and rear corners of the cutout portion, a sewing machine adapted to be received within said cutout, a power transmitting motor supported by said power-table and means operatively to connect said motor with said sewing machine; the improvement consisting in the provision of a unitary means for mounting said sewing machine within said table cutout, said unitary means comprising an insert adapted to be removably mounted within said table cutout, means for locking said insert to said table top, said insert having a

rectangular shaped cutout formed therein of a size and shape to accommodate said sewing machine and having openings at the corners thereof, ledges formed in the insert at the corners of the cutout for removably supporting the sewing machine thereon and cushioning pads on said ledges, said locking means including an elongated flat bar extending along the front long edge of the insert on its bottom surface and underlapping the adjacent edges of the table top, said bar having openings in line with the front corner openings of the insert, and in line with the front corner openings of the table top, bolts extending through said aligned openings, nuts on said bolts, flat bar brackets extending diagonally across the rear corners of the insert on the bottom surface thereof, said brackets having openings in line with the corner openings in the insert and the rear corner openings in the

table top, bolts extending through said latter aligned corner openings, and nuts on the ends of said bolts.
